UNITED STATES PATENT OFFICE.

FREDERICK HASBROUCK, OF NEW YORK, N. Y.

LABELING-MACHINE.

SPECIFICATION forming part of Letters Patent No. 540,489, dated June 4, 1895.

Application filed March 20, 1895. Serial No. 542,452. (No model.)

To all whom it may concern:

Be it known that I, FREDERICK HASBROUCK, of the city and county of New York, in the State of New York, have invented a new and useful Improvement in Labeling-Machines, of which the following is a specification.

My invention relates to an improvement in labeling machines, the object being to provide a simple and effective machine for attaching a label to the curved or inclined surface of a bottle or package and in providing mechanism for gumming the label before it is attached; the gumming and attaching mechanism being under the control of a single operating device.

A further object is to provide a device in which the label holder may be supplied with a quantity of labels of the required size, which may be held against displacement while the top label is being gummed and attached to the bottle or package.

A practical embodiment of my invention is represented in the accompanying drawings, in which—

Figure 1 is a front view of my machine, the table being partially broken away, the label-support being in its raised position as when attaching the label, and the gumming mechanism being in its withdrawn position. Fig.

2 is a similar view of the label-support in its lowered position and the gumming mechanism in its advanced position. Fig. 3 is a top plan view of the machine, the label-support being in its lowered position and the gumming mechanism in its withdrawn position. Fig. 4 is a side view of the machine, the table being in section, the label-support and its operating mechanism being shown in full lines in its raised position and in dotted lines

in its lowered position; and Fig. 5 is an enlarged view in section of a portion of the gumming-roller.

I have shown, and will describe my invention in connection with the labeling of bottles; but I would have it understood that it may be used with equal facility for labeling packages of many different kinds and shapes.

The table for supporting the several parts is denoted by A and it is provided with suitable legs a. Supported by the table and extending lengthwise thereof, is a suitable drive shaft B which may be rotated in any man-

ner, preferably by a suitable pulley and belt, as shown at b; or it may be driven by hand or foot power, if so desired.

The bottle to which the label is to be attached is denoted by C and it is supported in proper position by an uprising back or standard D, having a forwardly extending top d which partially surrounds the neck of the bottle C.

To the table A is hinged a label support E which is adapted to swing up into position to force a label around the body of the bottle C for attaching it thereto. This swinging label support E is cut away, as shown at e, so that the sides of the support E may swing up on opposite sides of the bottle C. The label support is further provided with a curved portion e' at its top for partially embracing the neck of the bottle to allow the support to swing into an approximate vertical position. This swinging label support E is raised and lowered by means of a suitable connecting rod F which extends through a slot a' in the table A and engages a crank b' on the shaft B. This connecting rod F is provided with an elongated slot f, whereby the label support E is allowed to rest in its lowered or horizontal position for about half of the revolution of the drive shaft B.

Across the cut away portion e' of the label support E, I stretch elastic straps G (preferably three in number) which serve to support the labels and as the label support is raised, wrap the labels around the bottle C. These elastic straps G are preferably rubber strips and they are clamped or secured to the label support at their opposite ends in any suitable manner.

The labels are denoted by H and they are held from sliding downwardly as the support E is raised by means of suitable projections I, I'. These projections have a lateral adjustment in suitable slots i, i', so that the projections I, I' may support longer or shorter labels H and at the same time clear the sides of the bottle as the label support is raised.

The labels H are held against lateral movement while they are being gummed and also held against toppling over as the support E is raised by means of a suitable spring clamp J, which preferably consists of two arms j, j' pivoted to lugs e², e³ on the support E and con-

55

nected at their outer ends by a rod j^2 . To the inner ends of the arms j, j' , I secure spring rods j^3, j^4 by means of suitable clamp nuts j^5 . These rods are preferably of spring material and can be adjusted laterally to accommodate different sizes of bottles. This clamp is held snugly against the top of the pile of labels by means of suitable springs j^6, j^7 which engage the arms j, j' respectively. The clamp J is released from the labels H as the label support E nearly reaches its raised position, by reason of the engagement of the rod j^2 with the neck of the bottle C , as shown clearly in Fig. 4.

15 Proceeding to describe the gumming mechanism, K designates a suitable gumming roller, which preferably consists of a perforated hollow cylinder, provided on its exterior with a gum applying cover k , preferably of felt. This gumming roller is preferably filled with an adhesive fluid through a suitable opening k' which is provided with a stopper k^2 . This adhesive fluid oozes out through the perforations in the cylinder and 25 saturates the cover k of the roller. This roller is provided with a suitable yoke piece L , which connects with a suitable slide M , which has a sliding movement in a guide way N on the table A .

30 The roller K is advanced and withdrawn across the top of the labels on the label support E by means of a rocking lever O , which is pivoted in a suitable support P depending from the table A . One end o of the lever O projects through a slot in the table A and 35 engages a pin m on the slide M , and the other end o' engages a cam b^2 on the drive shaft B . The groove in this cam is so arranged that, as the shaft B is rotated, the cam will advance and withdraw the roller over the top 40 of the labels H when the label support is in its lowered or horizontal position and will hold the roller K in its withdrawn position while the support E is being raised and lowered by reason of the crank and rod connection with the support.

45 In operation, a number of labels H are placed upon the label support E when it is in its lowered position and the machine is then started. The first part of the rotation of the shaft B will advance and withdraw the gumming roller K over the top label. The further rotation of the shaft B will raise the label support and bring the top label into contact

55 with the bottle C , where it will adhere. The still further rotation of the shaft B will allow the support E to swing down, and as it does so, the spring rods j^3, j^4 of the clamp J will engage the remaining labels and clamp them firmly to the support E during the remainder 60 of its downward movement.

It is evident that slight changes might be resorted to in the form and arrangement of the several parts without departing from the spirit and scope of my invention. Hence I do 65 not wish to limit myself strictly to the structure herein set forth, but

What I claim is—

1. In combination, a support for the article to be labeled, a swinging label support, means for raising and lowering the support, a gumming mechanism, and means for causing the gumming mechanism to traverse the label when the label support is in its lowered position, substantially as set forth. 7c

2. In combination, a support for the article to be labeled, a label support, a drive shaft for swinging the label support toward and away from said article and a gumming mechanism under the control of the drive shaft in 80 position to be advanced and withdrawn across the label when the label support is in its lowered position, substantially as set forth.

3. In combination, a support for the article to be labeled, a swinging label support for 85 attaching the label to the said article, means for swinging the label support toward and away from the article and adjustable projections on the label support for holding the labels from sliding downwardly when the label support is being raised and lowered, substantially as set forth.

4. In combination, a support for the article to be labeled, a label support having a movement toward and away from the said article, 95 a drive shaft and a gumming mechanism comprising a gumming roller, a slide, a connection between the roller and slide and a vibrating lever, one arm of which engages the slide and the other arm engages the cam on 100 the drive shaft, whereby—as the shaft is rotated—the gumming roller is caused to traverse the label on the label support, substantially as set forth.

FREDERICK HASBROUCK.
